UNITED STATES PATENT OFFICE.

OTIS KIRLIN, OF WEBSTER, DAKOTA TERRITORY.

AUTOMATIC BRAKE FOR WAGONS.

SPECIFICATION forming part of Letters Patent No. 372,682, dated November 8, 1887.

Application filed January 12, 1887. Serial No. 224,205. (No model.)

To all whom it may concern:

Be it known that I, OTIS KIRLIN, of Webster, in the county of Day and Territory of Dakota, have invented certain new and useful 5 Improvements in Automatic Wagon-Brakes; and I do hereby declare the following to be a full, clear, and exact description of the invention, such as will enable others skilled in the art to which it appertains to make and use the 10 same.

My invention relates to an improvement in automatic wagon-brakes.

The object is to provide a simple and inexpensive system of mechanism for attachment 15 to any wagon, which operates to automatically force the brakes into frictional contact with the wheels by the back-hold of the horses in descending a hill, and yet prevents the brakes from engagement with the wheels when the 20 wagon is being backed.

With these ends in view my invention consists in certain features of construction and combinations of parts, as will be hereinafter fully described, and pointed out in the claims. 25 In the accompanying drawings, Figure 1 is a view in longitudinal section of the wagon running-gear, showing the normal position of the brake-operating mechanism. Fig. 2 is a similar view of the front portion of the running-gear, 30 showing the position of the parts when the brake is applied, the dotted lines showing the position of the rocking shaft when engaged by the teeth of the hub-collar. Fig. 3 is a detached view of the hub-collar, and Fig. 4 is a detached 35 view of the whiffletree-bolt.

A represents a wagon running-gear, to the under side of which my improved brake mechanism is attached. A brake-operating rod, B, extending lengthwise of the tongue or pole C, 40 is loosely connected to the under side of the latter by the eyes a, allowing the free longitudinal movement of the rod, and a portion of the rod B is divided or has the slot a' near the forward end straddling the neck-yoke pin or 45 stop b, and terminates in the hooks c d, between which the ring of the neck-yoke is confined.

Beneath the rear end of the tongue C a bracket, D, is rigidly secured. This bracket 50 is preferably constructed with a pair of depending parallel skeleton plates, d' d'', and it may be secured to the tongue by means of clips

e or simply by bolts or screws. Between the plates d' d'' a lever, E, is pivoted, the upper end of the latter being bifurcated to receive 55 the rear end of rod B, which is pivoted therein. The lower end, e', of the lever E is similarly formed to receive the forward end of the draft-rod F, which is pivoted thereto, while a groove, f, furnishes a convenient recess in which the 60 draft-rod F lies when the brakes are applied.

The draft-rod F extends from the lever E to the rear axle, whereon a plate, G, bifurcated at the forward end and having a pair of jaws, g, is secured by clips G' or similar means. A 65 lever, H, is pivoted at its middle between these jaws g, and to the upper arm, h, of the lever the rear end of draft-rod F is loosely connected, while to the lower or opposite arm a rod or link, I, is pivotally secured. 70

A pair of arms, J, located on the reach a little in front of the rear wheels, project laterally from the reach. These arms J are grooved on the upper face to admit of the bar K, having the downwardly-bent ends k, rocking thereon. To these ends k the transverse bar L, carrying the brake-blocks l, is loosely hung, and the forward end of the link I is loosely secured to the bar L at its middle. 75 This manner of connecting the bar L to the reach is not essential, and, plainly, might be slightly varied.

From the description thus far disclosed it will be readily seen that immediately on the neck-yoke being held back by the horses, either 85 in descending a hill or in backing the wagon, the operating-rod B is forced back, reversing the lever E from its normal position, as shown in Fig. 1, thus carrying forward with its lower end the draft-rod F, which in turn reverses 90 the lever H, its lower end pulling back the link I, and with it the bar L, carrying the brake-blocks l in contact with the rear wheels; but a mechanism yet to be described limits the backward movement of the brake-blocks 95 to the holding back of the wagon while the latter is moving forward down an incline. The brake is instantaneously released from the wheels upon the draft being applied to the whiffletrees, owing to the eccentric formation 100 of the whiffletree-bolt shown in Fig. 4. The formation of this bolt is similar to a small crank-shaft, consisting of the shaft m, terminating at its lower end in the crank n and at

the upper end in a crank, *o*. On this upper crank, *o*, the whiffletree is mounted, the portion between the tongue and whiffletree being conveniently flattened, and the hasp *O* is secured over the end in the ordinary manner or by a pin extending transversely through it, and from the lower crank, *n*, arm *M* extends forward, and is connected to the rod *B* by an adjusting nut and sleeve, *N*, the object of the latter being to furnish an exact adjustment to the rod *B*, so that the cranks *n o*, being transverse of the tongue while the brakes are on, are turned forward when draft is applied, giving a forward movement to the rod *B* through arm *M*.

Rearward of lever *E*, and pivoted between plates *d' d'* of the bracket *D* in the slots *j*, is the dog *P*. This dog *P* is preferably wedge-shaped, and its smaller end, *p*, extends forward of its pivotal point, and is adapted to register with the shoulder *i*, formed in the rear of lever *E*.

A rocking shaft, *Q*, is loosely mounted in straps or suitable devices, *q*, on the front axle and extends toward one of the forward wheels, where it terminates in a short arm, *r*, which is normally held upward close to the axle by the spiral spring *r'*, as shown in Fig. 3. The inner end also terminates in an arm, *s*, which normally extends forward and slightly downward. The arm *s* is loosely connected with the upper rear end of the dog *P* by a connecting-rod, *x*, through which the shaft *Q* is rocked when the dog *P* is forced back to its full extent in the slots *j*. Now it will be seen that in descending a hill the back-pressure of the neck-yoke on the brake operating rod *B* forces the latter backward, giving the lever *E* a backward rock, which in turn forces the dog *P* backward in the slots *j* by reason of the forward pointed end of dog *P* registering with the shoulder *i* of the lever *E*, thus forcing the arm *s* slightly downward and the arm *r* on the opposite end of the shaft *Q* outward in the position shown in dotted lines in Fig. 3, to be engaged by the teeth *t* of hub-collar *T*, which, owing to the forward turn of the wheels, rocks the shaft still farther in the direction in which it has started, throwing the arm *s* still farther downward, and carrying with it the rod *x*, which latter tilts the forward end of dog *P* upward out of engagement with shoulder *i*, allowing the free backward rock of lever *E*, which operates the brake indirectly, as described. When the draft is applied to the whiffletree again, the rod *B* is drawn forward, as before described, regulating the position of lever *E* to receive the dog *P* behind the shoulder *i*, where the latter drops, the spiral spring *r'* having turned the shaft *Q* in adjustment to drop this dog *P*.

When the wagon is backed, it will be seen that the effect on the dog *P* is exactly opposite, the teeth *t* on the collar *T* tending to turn the arm *s* upward, thus holding the dog *P* firmly in engagement with the shoulder *i*.

The collar *T* is preferably made in sections hinged together at *u* and provided with adjusting-screw *v*, so as to admit of its being adjusted to the hub with slight difficulty.

It should have been mentioned that the draft-rod *F* may be in the form of an extension-rod, to allow of its being shortened or lengthened when the length of the reach is varied.

It is evident that slight changes might be resorted to in the form and arrangement of the several parts described without departing from the spirit and scope of my invention; hence I do not wish to limit myself to the particular construction herein set forth; but,

Having fully described my invention, what I claim as new, and desire to secure by Letters Patent, is—

1. The combination, with the running-gear and tongue, of the rod and lever mechanism for operating the brake-blocks, and the crank-shaped whiffletree-bolt for releasing the brakes, substantially as set forth.

2. The combination, with the running-gear and tongue, and draft and operating rods loosely secured thereto, the operating-rod being provided with an adjustable arm, of a crank-shaped whiffletree-bolt pivoted to the adjustable arm and adapted to move it forward with the draft on the whiffletree-bolt, substantially as set forth.

3. The combination, with the tongue and whiffletree and brake-operating rod secured to the tongue, of the whiffletree-bolt, substantially crank-shaped at either end, loosely connected to the operating-rod, for the purpose substantially as set forth.

4. The combination, with the bracket and lever pivoted therein, and the operating and draft rods pivoted one to each end of this lever, of a lever secured on the rear axle for converting the forward movement of the draft-rod to the backward movement of the brake-blocks, and the crank-shaped whiffletree-bolt adapted to release the brake when draft is applied thereto, substantially as set forth.

5. The combination, with a wheel-hub and a toothed hub-collar secured thereto, of a brake-locking mechanism adapted to be unlocked by the engagement of the hub-collar teeth with that mechanism, substantially as set forth.

6. The combination, with a spring-actuated rocking shaft having a pair of arms and a toothed collar secured to the wheel-hub, of a draft-connection secured to one arm for turning the opposite arm into engagement with the teeth of the collar, substantially as set forth.

7. A toothed hub-collar composed of sections hinged together and an adjusting screw or bolt for tightening the collar about a hub, substantially as set forth.

8. The combination, with the skeleton bracket and a dog loosely pivoted in slots therein, of a spring-actuated rocking shaft linked

to this dog, and a toothed hub-collar for operating this dog, substantially as set forth.

9. The combination, with the bracket, the shoulderered lever pivoted therein, and rod for operating said lever, of a dog loosely pivoted in this bracket, and suitable mechanism for regulating the adjustment of the dog, substantially as set forth.

In testimony whereof I have signed this specification in the presence of two subscribing witnesses.

OTIS KIRLIN.
